[57] CLAIM

The ornamental design for a vehicle body, as shown and described.

DESCRIPTION

FIG. 1 is a perspective front view of a automobile showing vehicle body of our new design;

FIG. 2 is a perspective view of the left side thereof with the right side being a mirror image;

FIG. 3 is a elevational view of the left side thereof with the right side being a mirror image;

FIG. 4 is a top view thereof;

FIG. 5 is a front view thereof; and,

FIG. 6 is a rear view thereof.

The wheels shown in broken lines in FIGS. 1-3, and 5-6 are shown for illustrative purposes only and form no part of the claimed design.
